UNITED STATES PATENT OFFICE.

GEORGE O. LEOPOLD, OF PHILADELPHIA, PENNSYLVANIA, ASSIGNOR TO NORTH BRO'S. M'F'G CO., OF PHILADELPHIA, PENNSYLVANIA, A CORPORATION OF PENNSYLVANIA.

LIFTING-JACK.

1,286,361.

Specification of Letters Patent.

Patented Dec. 3, 1918.

Application filed January 2, 1918. Serial No. 209,862.

To all whom it may concern:

Be it known that I, GEORGE O. LEOPOLD, a citizen of the United States, residing in Philadelphia, Pennsylvania, have invented 5 certain Improvements in Lifting-Jacks, of which the following is a specification.

My invention relates to certain improvements in lifting jacks, particularly of the type used in connection with automobiles. 10 One object of my invention is to make a substantial jack which will retain the load in any position in which it is elevated, and to make the jack so that it can be projected to a considerable height.

15 A further object of the invention is to provide means for allowing the jack to be quickly lowered, and also to allow the jack to be raised to a height without operating the gearing.

20 The invention also relates to details which will be fully described hereinafter.

In the accompanying drawings:

Figure 1 is a sectional elevation illustrating my improved lifting jack, the two plungers being partly raised;

Fig. 2 is a sectional plan view on the line 2—2, Fig. 1, with the shaft and worm wheel in full lines;

Fig. 3 is a sectional elevation on the line 30 3—3, Fig. 1;

Fig. 4 is a sectional plan view on the line 4—4, Fig. 1;

Fig. 5 is a sectional plan view on the line 5—5, Fig. 1;

35 Fig. 6 is a sectional plan view on the line 6—6, Fig. 1;

Fig. 7 is a sectional plan view on the line 7—7 Fig. 2;

Fig. 8 is an elevation of a portion of the 40 base partly in section, illustrating the inner plunger locked to the outer plunger;

Fig. 9 is a perspective view of the locking pawl by which the inner plunger is locked to the outer plunger;

45 Fig. 10 is a perspective view of the pawl carried by the outer plunger and arranged to engage the teeth of the inner plunger;

Fig. 11 is a perspective view of the plate which is located between the inner and outer 50 plungers and which prevents the rotation of the inner plunger in the outer plunger;

Fig. 12 is a perspective view of the pawl

for locking the pinion to the worm wheel shaft; and

Fig. 13 is a detached view of the handle 55 for operating the jack.

1 is a standard having a base 2. This standard is hollow and located in the standard is the outer plunger 3 having a rack 4 at one side which engages the pinion 5 60 loosely mounted on a shaft 6 carrying at one end the worm wheel 7. This shaft, worm wheel and pinion are mounted in a housing 8 forming part of the standard 1 in the present instance. The worm wheel 7 is 65 secured to the shaft 6 by a key 9 and pin 9^a.

Mounted within the outer plunger 3 is an inner plunger 10 having teeth 11 at one side with which the pawl 12 engages. This pawl is carried by the outer plunger 3. It will 70 be noticed that the toothed side of the inner plunger 10 is flattened, and carried by the outer plunger is a plate 13, Figs. 5 and 11, which fits between the inner and outer plungers, as shown in dotted lines in Fig. 1. 75

One face of this plate is flat and the other face is curved, so that when it is inserted in position, as in Fig. 1, it will prevent the inner plunger turning in the outer plunger, but will not interfere with the vertical 80 movement of the inner plunger. This plate 13 has an extension 14 turned up as at 15, and this turned up portion 15 is located in a slot 16 in the pawl 12 and acts as a guide for the pawl and also as a bearing for a 85 pressure spring 17, which is located in a cavity in the pawl and which tends to force the pawl into yielding contact with the teeth 11 of the inner plunger 10.

The teeth 11 are made as clearly shown in Fig. 1, having an abrupt lower edge and a beveled upper edge, so that the inner plunger can be lifted by hand or by any suitable tool, such, for instance, as the forked end 18 of the handle 19, Fig. 13, the handle being of sufficient length so that an operator can 90 reach in under an automobile and lift the inner plunger to the height desired.

Carried by the upper end of the inner plunger is a swiveled head 20 having a V- 100 groove 21, as shown, in the present instance, and having a curved projection 22 at one side which can be entered between the axle and the strainer rod of an automobile when

it is impossible to place the jack centrally under the axle.

At the lower end of the inner plunger 10 is a pivoted pawl 23 pressed out by a stiff spring 24. The pawl is hung in a bearing 5 by ears 25, Fig. 9, and the lip 26, at its lower edge, is arranged to engage the shoulder 27 at the lower edge of the outer plunger when the jack is entirely depressed, as 10 shown in Fig. 8.

A light leaf spring 28, in the present instance, is secured to the outer plunger and bears upon the edge of the lip 26, and, when in the normal lowered position, as 15 shown in Fig. 8, will have no effect upon the pawl 23, as the spring 24 is stronger than the spring 28, but when the outer plunger is raised to the position shown in Fig. 1, the spring 28 is forced against the 20 inner wall of the standard 1 and presses against the pawl 23 with sufficient force to overcome the pressure of the spring 24 and consequently the inner plunger is released from the outer plunger, as shown in said 25 Fig. 1, and the inner plunger can be raised by hand into position under the axle, or other element, of a vehicle, after which the outer plunger can be raised by the ratchet mechanism, which I will now proceed to 30 describe.

The worm wheel 7 is engaged by the worm 29 on a shaft 30 arranged at right angles to the shaft 6, Figs. 1 and 2, and this shaft is mounted in an extension 8^a of the housing 35 8 and has an enlarged portion 31 provided with ratchet teeth 32 which are engaged by a pawl 33, shown by dotted lines in Fig. 2, carried by the arm 34 mounted on the portion 31 of the shaft 30 and held in place 40 by a washer 35 and a screw 36. The shaft 30 is reduced at 37 and projects beyond the housing 8, as shown in Fig. 1, and a split ring is located between the housing and a washer 39 on the shaft, the washer being 45 held in place by a screw 40. The split ring frictionally holds the ratchet wheel while the pawl is on its return movement.

In order to lock the pinion 5 to the shaft 6, I provide a pawl 41, shown clearly in 50 Fig. 12, which has a tooth 42 beveled at one side. This tooth is arranged to enter one of the grooves 43 in the hub of the pinion 5. The pawl is located in a slot 44 in the shaft 6 and its inner end is notched to engage a 55 cross bar 45 carried by the shaft 6. A spring 51 bears upon the under side of the pawl 41 and tends to force the pawl into engagement with the pinion 5. The outer end of the pawl is beveled, as at 46, and a sleeve 60 47, adapted to slide on the projecting portion of the shaft 6, is arranged to engage the beveled outer end of the pawl and depress it, so as to retract the tooth 42 from engagement with the pinion 5. The pawl is 65 notched at 48 for the reception of a split

ring 49 located in a groove in the shaft 6. The sleeve 47 is retained on the shaft by a spring ring 50 located in a groove in the outer end of the shaft, as clearly shown in Fig. 3.

It will be seen by the above construction that the outer plunger can be raised and lowered by a ratchet movement and it is held in any position to which it is adjusted by the worm and worm gear. The ratchet device can be reversed, as in other types of ratchet mechanism, so as to raise the jack or lower it, and by the use of the spring pawl, which locks the shaft 6 to the pinion 5, the jack can be quickly lowered by merely 70 pressing upon the collar 47 so as to force the pawl out of engagement with the pinion 5, when the outer plunger will be lowered by its own weight carrying with it the inner plunger, and when the pawl 12 comes in 75 contact with the inclined face 52 of the standard 1 it is forced outward, releasing the inner plunger 10 from engagement by the pawl 12, and this plunger will drop by 80 its own weight.

Cushions may be provided for the two plungers and in the present instance I have shown a cushion 53 located in the bottom of the base 2 and held in position by a detachable plate 54 so as to cushion the plungers when they are dropped from an elevated position on pressing the collar 47. 90

If the jack is used as an automobile jack, the operation is as follows:—The jack is placed on the ground and, if possible, directly under one of the axles of the automobile so that the strain will be directly on the plungers, but if there is a strainer rod then it may be necessary to engage the axle by the curved projection 22, the base being 100 so designed as to properly support the load.

The outer plunger is raised by the ratchet mechanism to the point indicated in Fig. 1, where the spring 28 forces the pawl 23 carried by the inner plunger out of engagement 110 with the outer plunger by coming in contact with the inner wall of the standard 1, then the inner plunger can be raised by merely pulling up on the head so as to bring the head directly under the axle, and the forked end 18 of the handle 19 may be used for this purpose, particularly where it is difficult to gain access to the jack. After the head has been properly located in position, the handle 19 is placed in the socket 53 in the arm 34 115 and the arm reciprocated, causing the shaft 30 to be turned and this shaft imparts movement to the shaft 6 through the worm and worm wheel and as the pinion 5 is locked to the shaft 6 by the pawl 41 it will be 120 turned and the outer plunger 3 raised, lifting the axle of the automobile to the desired height so that the wheel will be clear of the ground. The jack will hold the axle in the elevated position as it is locked by the worm 125 130

and worm gear, but, on reversing the pawl 33, the movement of the shaft 30 can be reversed and the outer plunger can be lowered, lowering the axle and when the plunger

5 ger is lowered so that the pawl 12 comes in contact with the inclined surface 52 of the standard 1, the inner plunger will be released and both plungers will then be in their lowest positions.

10 If it is desired, however, to release the outer plunger without using the ratchet mechanism, the collar 47 can be pushed in so as to release the pawl 41, when both plungers will drop into their lowest positions.

15 I claim:

1. The combination in a lifting jack, of a standard; a toothed outer plunger mounted within the standard; a pinion meshing with the teeth of the outer plunger; a worm and 20 worm gear for turning the pinion so that the plunger can be adjusted and held in its adjusted position; an inner plunger mounted in the outer plunger and having ratchet teeth; a pawl carried by the outer plunger

25 and arranged to engage the teeth of the inner plunger so as to hold the inner plunger in its raised position; and means for automatically releasing the pawl from engagement with the inner plunger when the outer 30 plunger is lowered to its fullest extent.

2. The combination of a standard, an inner and an outer plunger mounted in the standard, teeth on each plunger; the teeth on the inner plunger being in the form of 35 ratchet teeth, a spring pawl carried by the outer plunger and engaging the teeth of the inner plunger, a transverse shaft having its bearings in a housing carried by the standard; said pinion engaging the teeth of 40 the outer plunger, a shaft on which the pinion is loosely mounted, a pawl located in the shaft and arranged to engage the pinion so as to lock the pinion to the shaft, means for turning the shaft, and means 45 for withdrawing the pawl from engagement with the pinion so as to allow the outer plunger to drop to its normal position.

3. The combination of a standard; an inner and an outer plunger mounted in the standard; teeth on each plunger, the teeth on the inner plunger being in the form of ratchet teeth; a spring pawl carried by the outer plunger and engaging the teeth of the inner plunger; a transverse shaft having 55 its bearings in a housing carried by the standard, said pinion engaging the teeth of the outer plunger; a shaft on which the pinion is loosely mounted; a pawl located in the shaft and arranged to engage the pinion so as to lock the pinion to the shaft; means for turning the shaft; means for withdrawing the pawl from engagement 60 with the pinion so as to allow the outer plunger to drop to its normal position, said 65 standard having a portion arranged to force

the spring pawl carried by the outer plunger from engagement with the teeth of the inner plunger so that it will also drop to its normal position.

4. The combination in a lifting jack, of a standard; an outer, hollow plunger mounted within the standard; teeth on said plunger; an inner plunger mounted within the hollow, outer plunger and having ratchet teeth; a pawl plate mounted in a slot in the upper 70 end of the outer plunger and engaging the teeth of the inner plunger, said inner plunger being flat on the toothed side; a half round plate mounted between the flattened portion of the inner plunger and the outer plunger, and having an extension projecting through the outer plunger, the ends of the projection being turned up; a coiled spring mounted between the turned up portion and the pawl plate, and tending to 75 force the pawl plate into yielding engagement with the teeth of the plunger; a pinion engaging the teeth of the outer plunger; and means for turning the pinion.

5. The combination of a standard; a plunger having teeth at one side; a housing; a pinion mounted in the housing and meshing with the teeth of the plunger; a shaft on which the pinion is loosely mounted; a worm wheel secured to the shaft and 95 also mounted in the housing; a pawl carried by the shaft and arranged to engage the pinion; means for releasing the pawl so as to disengage the pinion from the shaft; a shaft at right angles to the first mentioned shaft and mounted in the housing; 100 a worm on said last mentioned shaft meshing with the worm wheel; and means for turning the worm shaft.

6. The combination in a lifting jack, of a standard; an inner and an outer plunger, each having teeth, the teeth of the inner plunger being in the form of ratchet teeth; a pawl on the outer plunger engaging the teeth of the inner plunger; a pinion mounted on the standard and arranged to engage the teeth of the outer plunger; a pawl on the lower end of the inner plunger arranged to engage the outer plunger; a spring for 110 yieldingly holding the pawl in engagement with the outer plunger; and means for releasing the pawl when the outer plunger is raised a given distance so that the inner plunger can be lifted from this point by hand.

7. The combination in a standard, of an inner and an outer plunger; each plunger having teeth, the inner plunger having ratchet teeth, a pawl on the outer plunger arranged to engage the teeth of the inner 125 plunger, a pinion mounted on the standard engaging the teeth of the outer plunger, a pawl on the lower end of the inner plunger arranged to engage the outer plunger, a spring tending to hold the pawl in yield- 130

ing engagement with the outer plunger, and a spring carried by the outer plunger bearing against the pawl and shaped so as to be engaged by the inner wall of the standard when the outer plunger is raised so as to press the pawl out of engagement with the outer plunger and to allow the inner plunger to be raised.

8. The combination in a lifting jack, of a standard; an inner and an outer plunger mounted in the standard, each plunger having teeth, the teeth of the inner plunger being ratchet teeth; a pawl on the outer plunger arranged to engage the teeth of

the inner plunger, the standard having a beveled portion arranged to force the pawl out of engagement with the teeth of the inner plunger when the outer plunger is lowered; a head carried by the inner plunger; means for coupling the two plungers when they are in their lowest positions; means for releasing the inner plunger when the outer plunger is raised a given distance; a pinion meshing with the teeth of the outer plunger; and means for turning the pinion.

In witness whereof I affix my signature.

GEORGE O. LEOPOLD.
